UNITED STATES PATENT OFFICE.

LUDWIG WINTERHALDER, OF NEUSTADT, GERMANY.

ICE-SPUR.

SPECIFICATION forming part of Letters Patent No. 736,468, dated August 18, 1903.

Application filed April 8, 1902. Serial No. 101,908. (No model.)

To all whom it may concern:

Be it known that I, LUDWIG WINTERHALDER, manufacturer, a subject of the German Emperor, residing at Neustadt, (Schwarz-
wald,) in the German Empire, have invented
certain new and useful Improvements in Ice-
Spurs; and I do hereby declare that the following
is a full, clear, and exact description.

The present invention relates to ice spurs
or cramps which can be conveniently and
easily fixed to the boot-heel.

They consist, essentially, of two clamps ad-
justable toward or in one another, each of
which grasps the heel on one side, and of the
spur itself, which is made in the form of a
plate sharpened to an edge below and adjust-
able vertically. This plate is pushed down
for use.

In the new ice-spur the arrangement is such
that the same part serves for fixing the device
to the boot-heel and also for keeping the spur
itself in its operative position.

The invention is illustrated in the accom-
panying drawings, Figures 1 to 6 showing one
constructional form, and Figs. 7 to 13 another
form of construction, of the new ice-spur.
Fig. 1 shows the first pattern of ice-spur seen
from below. Figs. 2 and 3 are respectively
sections on the lines A B and C D of Fig. 1.
Fig. 4 is an end view of the spur. Figs. 5 and
6 illustrate the spur from above in the open
and closed positions, respectively. Fig. 7 is
a partially-sectional view of the spur of the
second pattern seen from above. Fig. 8 is a
plan view, and Fig. 9 is an end view, of the
same. Figs. 10 and 11 are respectively front
and side views, on an enlarged scale, of a de-
tail. Figs. 12 and 13 illustrate the fixing and
releasing of the actual spur.

Adjustable in the clamp *a*, which grasps
the boot-heel with the spikes on its upwardly-
bent flanges *b*, is the second clamp *c*, Fig. 2.
A plate *e* is connected by screws *d* with the
clamp *a*, in which plate is a longitudinal slot *f*.

The plate *e* is held at a certain distance from
the clamp *a* by means of intermediate pieces
g and *h*. The clamp *c*, which is also provided
with spikes for engaging in the heel, on its
upwardly-bent flanges has a slot *k*, Figs. 5 and
6, which on one longitudinal side is smooth and
on the other provided with a kind of toothing.

In the space between the clamp *a* and the

plate *e* is the lever *l*, which is provided on its
upper side with a wing *m* and on its lower
side with a stud *n*. The stud serves for en- 55
gaging in the slot *f* and the wing for engaging
in the toothing of the slot *k*.

The plate *o*, forming the ice-spur itself, is
movable vertically between the flaps *b* of the
clamp *a*. It can be fixed by means of the 60
lever *l* in two positions, engaging in one or
other of the lateral slots *p* thereof in the
closed position. The plate *o* is sharpened
below and serves as ice-cramp.

If the ice-spur is to be attached to the boot-
heel, it is placed against the heel, the lever *l*
being in the position shown in Fig. 6, and the
two clamps *a* and *c* are pressed together until
their spikes begin to press into the heel. This
longitudinal movement is possible without 70
anything further, as the wing *m* of the lever
l when in the open position is not in engage-
ment with the toothing of the slot *k*. The le-
ver *l* is then moved in the direction of the
arrow, whereby the wing *m* first engages in 75
one of the notches of the toothing of the slot
k. The lever *l* is consequently coupled there-
by with the clamp *c*, as owing to the stud *n*
moving in the slot *f* the wing *m* cannot be
forced out of the toothing. If the lever is 80
turned farther, its inner end comes against
the intermediate piece *h*, rigidly connected
with the clamp *a*. Consequently the clamp *c*
is moved toward the clamp *a*, and therefore
against the heel, the clamp *a* and its spikes 85
pressing firmly into the boot-heel. On this
movement the lever *l* passes into a slot *p* of
the plate *o*, so that when it is completely re-
versed, Fig. 4, it securely fixes the whole de-
vice on the boot-heel and at the same time 90
keeps the ice-spur itself—that is, the plate *o*—
in its position. If the ice-spur is to be re-
moved, it is only necessary to turn the lever *l*
in the opposite direction to the arrow, where-
upon the ice-spur can easily be released from 95
the heel.

It is possible to use the same ice-spur for
large and small heels, owing to the arrange-
ment of the slot *k* having several teeth instead
of only one.

In the second constructional form, Figs. 7 to
13, a screw *q* serves for the mutual adjust-
ment of the two clamps *a* and *c*, which en-
gages at one end with a matrix provided in-

2

side the clamp *c*. At the other end it is so arranged in the clamp *a* that it can easily rotate, but neither move toward the inside nor outside, which, for instance, can be effected by means of a band on the outer side of the clamp *a* and a stud on the inner side thereof. The ice-spur itself is again made in the form of a plate *o*, movable in the upwardly-bent part of the clamp *a*. It has an oval slot *r*, through which the end of the screw *q* passes. The slot is widened out laterally at its upper and lower ends. The screw *q* where it engages in the slot *r* is flattened. This is arranged so that the plate *o* can only be moved when the flattened part is in the same direction as the slot *r*, Fig. 13. If the screw is twisted out of this position, which is only possible in the two end positions of the plate *o*, the latter is fixed thereby in its then position. In the new ice-spur, therefore, the attachment to the boot-heel and the fixing of the spur itself are combined in a very simple manner.

Of course many of the details of the new ice-spur can also be carried out in other ways without departing from the principle of the present invention.

Having now described my invention, what I claim as new, and desire to secure by Letters 30 Patent, is—

1. In an antislapping device, the combination with two adjustably-connected plates having upwardly-extending projections on their opposite ends, said projections on one of 35 said plates having grooves formed in the inner edges thereof, of an ice-spur adapted to slide within said grooves, substantially as described.

2. In an antislapping device, the combination with two adjustably-connected plates forming a clamp, an ice-spur carried thereby and a plate secured beneath said clamp of a lever pivoted between said clamp and said plate, said lever having an adjustable connec-

tion with one plate of the clamp and being 45 adapted to press against a part of the other plate of the clamp, substantially as described.

3. In an antislapping device, the combination with a two-part clamping-plate, a slot formed therein, one edge of said slot having a 50 series of recesses therein, an ice-spur secured to said clamping-plate, and a plate secured beneath the said clamping-plate and having a slot therein, of a lever having a stud on one side thereof adapted to slide in the slot in said 55 lower plate and a projection on the opposite side of said lever adapted to slide in the slot in said clamping-plate and to engage the recesses therein when said lever is moved, substantially as described.

4. In an antislapping device, the combination with the clamp comprising two adjustable plates, a plate secured beneath said clamp, a cross-bar between said clamp and said plate and a lever pivoted between said 65 clamp and said plate and having a cam-shaped portion bearing against said cross-bar and also having a lug *m* engaging one of the adjustable plates, of an adjustable ice-spur secured to said clamp and having recesses therein 70 adapted to be engaged by said lever, substantially as described.

5. In an antislapping device, the combination with the clamp comprising adjustable plates and the adjustable ice-spur carried by 75 one of said plates, slots in the spur of a lever connected adjustably to one plate and adapted to press against the other plate and also arranged to engage the slots in the ice-spur.

In witness whereof I have hereunto set my 8c hand in presence of witnesses.

LUDWIG WINTERHALDER.
